UNITED STATES PATENT OFFICE.

JACK BURNABY DICKSON AND WILBERT LESLEY AMY, OF WOODSTOCK, ONTARIO,
CANADA.

STEAMER.

Application filed May 10, 1928. Serial No. 276,692.

The invention relates to improvements in steamers as described in the present specification and shown in the accompanying drawings which form part of the same.

5 The invention appertains particularly to steamers for bread rolls for what is conventionally known as "hot dogs".

10 The object of the invention is to provide an efficient and serviceable steamer for rendering bread rolls more palatable and moreover that can be used for restoring stale rolls and in practice it has been found that with this steamer rolls that are even a week old may be refreshed without making them in 15 any way soggy.

A further object of the invention is to provide a portable steamer that may be heated by any heat source—electric, gas, coal-oil stove et cetera—and one that is particularly suitable for use at highway refreshment booths where a portable steamer of this nature is largely needed.

Referring to the drawings, Figure 1 is a side elevation of the steamer.

25 Figure 2 is a vertical section thereof.

Figure 3 is a plan view with the cover removed showing the basket for holding the rolls and a steam-coil for steaming the same.

30 Figure 4 is a fragmentary vertical sectional view illustrating the steam coil connected up with the boiler.

Figure 5 is a transverse sectional view taken on the line 5—5 of Figure 2.

Like numerals of reference indicate corresponding parts in each of the figures throughout the drawings.

In the drawings, the reference numeral 10 generally indicates the body of the device which is of cylindrical shape and has a flat 40 bottom 11 for resting on a heater. The top of the body is open and the edge is beaded as at 12 in order to reinforce it. 13 is a shell of smaller girth than the body 10 and located therein. This shell has a bottom 14 spaced from the body bottom 11. The shell 45 is considerably smaller in depth than the body and its top is flanged as at 15. This flange is annularly shaped and approaches closely to the inner surface of the body 10.

50 A gasket 16 of suitable material is placed between the flange and the inner surface of the body and the flange is riveted or otherwise secured by means of securing elements 17 in order to form a water-tight joint.

55 The shell together with the body 10 defines

a boiler 18. This boiler is provided with an inlet 19 shown in the form of an elbow which is closed by a cap 20 of the screw type. It is to be understood that in the event of running water being available the 60 cap 20 may be dispensed with and the inlet connected with the running water. It will of course be necessary to employ some form of valve as conventional to appliances of this kind in order that the water may be 65 turned on and off.

The boiler may be provided with a water gauge 21 or any other fittings conventional to steamers.

22 is a container of cylindrical shape and 70 smaller diameter than the shell 13. The container is positioned centrally within the body 10 and has its top on a level with the top thereof. The container has a floor 23 spaced from the shell bottom 14 and is supported in the body by an outwardly projecting flange 24 that rests on the top edge 12 of the body. The flange 24 is provided with a circular series of holes 25. Between the container and the body is a circular hot-air chamber 26.

27 is a receptacle shown in the form of a reticulate basket such as wire mesh. This basket is of slightly smaller size than the container and is fitted therein supported on 85 legs 28.

29 is the steam coil which is located in the vicinity of the top of the basket and consists of an approximately circular tube, preferably in the form of a slight spiral. 90 This coil is placed between the container and the basket and has minute openings 30 arranged lengthwise so as to direct steam jets downwardly onto the rolls.

Referring particularly to Figure 4; one 95 end of the coil is connected to a piping 31 that extends through the container and the cylindrical portion of the body and is then directed downwardly to the boiler 18 communicating with the steam space thereof as 100 at 32. The other end 33 of the coil is connected to a pipe 34 that also extends through the container and the body 10 and has an external pet-cock 35 by which it can be opened and closed. The coil slopes downwardly from its inlet end to the outlet end so that any steam condensing therein may be run off through the pet-cock 35.

36 is a lid of conical shape which has a downwardly turned edge 37 fitting over the 110

beading 12 of the cylindrical body. The apex is provided with a handle 38 by which it may be removed. 39 is a lining likewise of conical shape and spaced apart from the 5 lid proper so as to provide a hot air compartment 40. The lower edge of the lining has a downwardly turned flange 41 that fits inside the container. This lining closes the top of the container and is rigidly affixed to 10 the lid proper by spacers as at 42. The hot air space communicates with the hot-air chamber 26 of the body through the openings 25 in the flange 24. By this construction the interior of the container is completely surrounded by hot air space which 15 serves to prevent condensation of the steam and the attendant formation of water within the container which would injure the contents of the basket.

20 In the use of this steamer, the boiler 18 is partly filled with water which is admitted through the inlet 19 and upon being heated generates steam which rises and fills the space above the water. Steam is conducted 25 through the pipe 31 to the coil 29 and escapes in the form of fine sprays or jets through the apertures 30 therein, being precipitated downwardly onto the rolls within the wire basket 27. The hot-air chambers surrounding the container prevents the condensation 30 of the steam as previously recounted.

While this invention has been described as particularly applying to the heating of rolls it is equally susceptible of being used for 35 other steaming purposes.

What we claim is:—

1. A steamer of the class described comprising a boiler for steam generation, a container disposed thereover and externally 40 heated thereby, a reticulate basket therein

for containing articles to be steamed, a lid for closing the container, and a steam coil encircling the basket and having perforations for diffusing steam upon the contents thereof, said steam coil being connected to 45 the boiler.

2. A steamer of the class described comprising a body, the lower part of which is divided off into a boiler for steam generation, a container within the body substantially surrounded by hot air space, a reticulate basket fitted within the container, a perforated steam coil encircling the basket, said steam coil being connected with the 50 boiler, and a lid for closing the container. 55

3. A steamer of the class described comprising a hollow body provided with a flat bottom and an open top, a shell of lesser girth and depth located within the body, said shell having a bottom spaced from the body 60 bottom, a flange projecting from the shell and secured to the body, said shell thus forming a boiler in the bottom portion of the body, a water inlet for the boiler, a container situated within the body and isolated 65 from it and the shell by a hot air space, a perforated flange projecting from the container and resting upon the top of the body, a reticulate receptacle within the container, a perforated sloping coil encircling the receptacle, a pipe connecting an end of the coil to the boiler, and a double walled lid fitted to the body so that the space between the walls communicates with the aforesaid 70 perforations in the container flange. 75

Signed at Woodstock, Ontario, Canada, this 26th day of April, 1928.

JACK BURNABY DICKSON.
WILBERT LESLEY AMY.
